United States Patent Office

Des. 214,318
Patented June 3, 1969

214,318

ELECTRICAL CLOSET

Henrik Carl Wilhelm Wahlfors, Stockholm, Sweden, assignor to AB Hakanssons Industrier, Amal, Sweden

Filed Dec. 26, 1967, Ser. No. 9,912

Term of patent 14 years

Int. Cl. D23—02

U.S. Cl. D23—48

Fig.1

Fig.2

Fig.3

Fig.4

FIG. 1 is a front view of an electrical closet showing my new design;

FIG. 2 is a top view thereof;

FIG. 3 is a left side elevational view thereof; and

FIG. 4 is a right side elevational view thereof.

I claim:

The ornamental design for an electrical closet, as shown.
